UNITED STATES PATENT OFFICE.

TULLY LA TESSA, OF CHICAGO, ILLINOIS.

DESIGN FOR A LAMP ARM.

Application filed August 17, 1927. Serial No. 23,118. Term of patent 7 years.

To all whom it may concern:

Be it known that I, TULLY LA TESSA, a citizen of the United States, residing at Chicago, in the county of Cook and State of Illinois, have invented a new, original, and ornamental Design for a Lamp Arm, of which the following is a specification, reference being had to the accompanying drawing, forming part thereof, in which the figure is a front view of the lamp arm.

I claim:

The ornamental design for a lamp arm, as shown.

In witness whereof I affix my signature.

TULLY LA TESSA.
